UNITED STATES PATENT OFFICE.

DANIEL H. LEVAN, OF BELLEFONTAINE, OHIO.

SILO-ROOF-ELEVATING DEVICE.

1,188,289.

Specification of Letters Patent. Patented June 20, 1916.

Application filed February 15, 1913. Serial No. 748,645.

To all whom it may concern:

Be it known that I, DANIEL H. LEVAN, a citizen of the United States, residing at Bellefontaine, in the county of Logan and State of Ohio, have invented new and useful Improvements in Silo-Roof-Elevating Devices, of which the following is a specification.

This invention relates to silos, and it has particular reference to an improved device for elevating the roof of a silo in order to enable material to be placed therein, after which the roof may be again lowered for the purpose of protecting the contents.

A further object of the invention is to so construct the improved device that the roof actuated thereby, when lowered, shall be firmly secured or locked in position, as against accidental displacement.

With these and other ends in view which will readily appear as the nature of the invention is better understood, the same consists in the improved construction and novel arrangement and combination of parts which will be hereinafter fully described and particularly pointed out in the claims.

In the accompanying drawings has been illustrated a simple and preferred form of the invention, it being, however, understood that no limitation is necessarily made to the precise structural details therein exhibited, but that changes, alterations and modifications within the scope of the claims may be resorted to when desired.

In the drawings, —Figure 1 is a side elevation, showing the invention as applied to a silo of ordinary cylindrical construction and showing the roof elevated. Fig. 2 is a vertical sectional view of the same, showing the roof lowered. Fig. 3 is a top plan view. Fig. 4 is a horizontal sectional view taken on the line 4—4 in Fig. 1. Fig. 5 is a side elevation taken at right angles to Fig. 1 with the roof lowered. Fig. 6 is a sectional detail view taken on the line 6—6 in Fig. 1.

Corresponding parts in the several figures are denoted by like characters of reference.

The silo 1 may be of cylindrical or of any other form and of any suitable and convenient construction. Said silo is provided with a roof structure 2 which is entirely independent of the side walls, said roof structure being provided at opposite sides thereof with downwardly extending arms or brackets 3, 3' which are connected with the roof by means of obliquely disposed rein-

forcing braces 4, 4'. The arms 3 are guided through keepers 5, 5' and 6, 6' on the sides of the silo wall, the uppermost keepers 5 being provided with guide wheels 7 which are suitably supported for rotation thereon.

Mounted for rotation in suitable bearings consisting of brackets 8 mounted on one side of the wall of the silo or in any other convenient location are winding drums 9 and 10 having intermeshing gears 11. The gear associated with one of the drums also meshes with a worm 12 which may be turned by means of a crank 13. A flexible element, such as a rope or cable 14, is connected at one end with the drum 9, and said rope or cable is guided over the guide wheel 7 associated with the keeper 5 at one side of the silo, the other end of said rope or cable being connected with the lower end of the arm 3 guided through said keeper and through the keeper 6 below the same. A similar flexible element, such as a rope or cable 15, is connected at one end with the drum 10, said rope or cable being guided over a series of suitably arranged flanged guide wheels 16 and over the guide wheel 7 supported by the keeper 5' at the opposite side of the silo, the other end of said rope or cable being connected with the lower extremity of the arm 3' guided through the said keeper 5' and through the keeper 6' below the same.

It will be evident that by manipulating the crank 13 in one direction, the drums 9, 10 will be rotated to wind thereon the ropes or cables 14, 15, thereby lifting or raising the roof, as will be seen in Fig. 1. By rotating the crank in the opposite direction the roof will be lowered by gravity. For the purpose of assisting in lowering the roof, the lower end of the arm 3 is connected by a flexible element, such as a rope 17, with the drum 9 in such fashion as to wind on said drum reversely to the rope 14. It follows that when the crank 13 is manipulated for the purpose of lowering the roof, it will not only be lowered by gravity, but also by the stress exerted by the rope 17. Said rope 17 may be duplicated by a similar rope connecting the lower end of the arm 3' with the drum 10, suitable guiding means being provided with such rope. The rope 17 will not only serve to positively lower the roof of the silo against the upward pressure of the contents of the silo, but it will also serve to lock the roof securely in any position to which it may be adjusted, by prevent-

ing movement in a reverse direction to that caused by the hoisting elevating tackle.

Suitable hoisting tackle including a block 18 and a rope or cable 19 supporting a grasping device in the nature of a pair of tongs 20 and a pulley block 21 supporting the same may be associated with the roof of the silo to be utilized for the purpose of elevating a pipe or duct through which ensilage 10 may be conducted into the silo by means of a blower or in other suitable fashion. It is evident that when the roof of the silo is raised, said hoisting tackle will be raised together therewith so as to be available for 15 the purpose indicated.

It is obvious that within the scope of the appended claims the precise construction of the operating tackle and the manner of mounting it with respect to the silo may be 20 greatly varied, and no limitation is intended in this respect.

Having thus described the invention, what is claimed as new, is:—

1. A silo comprising a wall, guides secured to the wall adjacent the upper end thereof, a movably supported roof 25 slideable through said guides, a pulley journaled in each of said guides, a drum mount-

ed upon said wall for rotation, means for rotating said drum, cables having one of their ends fixed to the drum and their opposite ends secured to the roof, said cables passing over the pulleys and operating to raise the roof when the cables are wound upon the drum, means for holding said roof at 35 any degree of elevation, and an additional cable having one terminal secured to the roof and the other terminal connected with the drum and adapted to be wound thereon when the drum is rotated in an opposite direction for forcibly lowering said roof. 40

2. A silo comprising in combination a wall structure, a roof structure supported and guided for vertical movement, means for elevating the roof structure for the admission of material, and means for forcibly moving said roof structure in a downward direction against upward pressure of the contents of the silo. 45

In testimony whereof I affix my signature 50 in presence of two witnesses.

DANIEL H. LEVAN.
